GASOLINE PRODUCTS COMPANY, INC., OF WILMINGTON, DELAWARE, A CORPORATION
OF DELAWARE

METHOD AND APPARATUS FOR TREATING HYDROCARBONS

Application filed July 17, 1928. Serial No. 293,322.

This invention relates to the conversion of oils and pertains more specifically to a process and apparatus for converting relatively heavy hydrocarbon oil bodies into commercial gasoline-like fractions.

The major purpose of this invention is to provide a treatment for heavy or high boiling point hydrocarbon oils in which the oil is subjected to heat and pressure conditions of such character and magnitude as will cause conversion of the oil, that is to say will insure the formation of appreciable quantities of lower boiling point hydrocarbons.

Another object of the invention is to exercise an accurate control of the thermal conditions obtaining in the separate stages of the process.

A further object is to efficiently and cheaply govern the character of the vapors which are condensed to produce the final distillate.

Yet another object is to distill off the lighter fractions of the synthetic crude by utilization of heats developed in the heating stage.

A further object is to control the evaporation of lighter fractions from the synthetic crude.

With these and other equally important objects in view, the invention comprehends the idea of cracking relatively heavy oil by subjecting it to such temperature and pressure conditions as will cause the conversion to take place substantially in liquid phase, and passing the fluid products of conversion to a reduced pressure stage wherein the contained heat of the oil is utilized for the distillation of lighter products. In the distillation stage the temperature of the synthetic crude is modified and the character of overhead products thus controlled. In the preferred method of operation this thermal modification is accomplished by utilizing certain fractions of the oil which is undergoing treatment and thus obtain a continuous and, so to speak, self contained process.

To enable a ready comprehension of the underlying principles of the invention there is shown in the accompanying drawings an apparatus which effectively carries out the several steps. This apparatus is shown diagrammatically and is to be taken as typifying

any comparable system which will function in an equivalent manner. In these drawings;

Fig. 1 is a diagrammatic side elevation view of the complete unit;

Fig. 2 is a detail view of a section of the unit which is connected to the evaporating tower;

Fig. 3 is a detail view showing a modified form of the apparatus disclosed in Fig. 2.

It has been proposed, heretofore, to carry out the conversion of oil by passing it through heating tubes to a reaction stage while imposing pressures of the magnitude of thirty atmospheres or more, and then distilling off the lighter fractions by a quick reduction of pressure. In carrying out such a process, however, a large quantity of the heavier fractions are distilled off, and hence an unnecessarily heavy load is imposed upon the dephlegmator or fractionating apparatus.

In addition to this a deposit of carbonaceous material of very high viscosity settles out in the evaporating stage. In some instances, as where the temperature of the synthetic crude is very high, the distillation may be so complete as to leave a solid cokey residue in the evaporating tower. Material in this form, as is known, is most difficult to remove and necessitates an expenditure of considerable time and labor in its removal.

In accordance with the present invention these disadvantages are obviated by modifying the temperature of the synthetic crude, to any desired degree, by the introduction of a cooler relatively carbon-free hydrocarbon medium. The preferred economical and efficient method of achieving this temperature control comprises the introduction into the synthetic crude of a quantity of hydrocarbon oil which has been preliminarily treated to free it of any suspended carbon which has been cooled to the desired extent.

Such a method is peculiarly advantageous; not only does it permit the attainment of a definite control of the extent or degree of vaporization, but it also insures a high fluidity of the unvaporized material in the evaporating stage and hence facilitates the subsequent handling of such fractions.

The apparatus which may be utilized to

effectuate the process includes a furnace, designated generally by the numeral 1. This may be provided with a baffle wall 2 which divides the furnace into combustion chamber 3 and tube chamber 4. The furnace is heated by means of a plurality of burners 5 which may be supplied with any desired kind of fuel such, for example, as gas or fuel oil.

Positioned within the tube chamber is a plurality of heat resistant tube sections 6 which are connected to form a continuous sinuous coil. The several sections constituting the coil may be so positioned with respect to each other and to the contiguous furnace walls as to insure the optimum conditions of heat transfer. The heating coil is operatively associated with the other elements of the apparatus by an inlet line 7 and a discharge or outlet line 8.

The operation of this furnace will be understood by those skilled in the art. The fuel is ignited in the combustion zone 3 and the hot gaseous products of combustion are deflected over the bridge wall, passing downwardly over the several heating tubes and outwardly through the flue 9 and stack 10. Since the tubes are confined within a closely adjacent and substantially coextensive chamber, full use is made of the radiant as well as the convective heat.

The heating tubes are supplied with oil from a plurality of sources. As shown in the drawings, a feed line 11 leads from a source of supply (not shown) to a charging pump 12. The discharge side of the pump is connected to a continuation 13 of the feed line which leads to and communicates with the inlet pipe 7. This line 13, as shown, is convoluted as at 14 to form a preheating coil. This coil is positioned in the upper section of the evaporator and adjacent the vapor discharge end.

A second and independent feed line 15 is connected to a charging pump 16. This feed line and pump is mounted in communication with the furnace inlet line 7 by the branch line 17. The line 15 serves as a conduit for oil from certain elements of the apparatus, in a manner to appear more fully hereinafter.

The discharge side of the heating stage communicates with the reaction zone through which the oil is moved at such a rate as to provide the necessary period of time to complete the conversion reactions. This time factor may be insured by passing the oil through an elongated tubing in which the desired temperature and pressure is maintained, or by utilizing an enlarged reaction chamber in which the speed of flow is reduced and the oil thus retained for the requisite period under conversion conditions. In the present process the second method is preferred. This is effectuated by utilizing an enlarged reaction chamber 18 suitably emplaced on supporting piers 19.

This chamber is preferably formed from a single piece of metal, having high tensile strength, low corrodibility and reactive characteristics. The metal may be extruded or otherwise treated to produce a unitary elongated container of substantially uniform metallic texture, free from seams, laps and other defects. Preferably the container is shaped with bottle-neck ends 19, which are suitably flanged to receive removable end closures. The chamber is tapped to receive a pressure gauge 20 and, if desired, any preferred type of temperature indicating device (not shown).

The chamber is connected with the heating unit by the line 8. As shown, the discharge end of this line communicates with the adjacent end of the reaction chamber. The other end of the chamber is connected by a discharge line 21 to an evaporator 22. Interposed in the chamber discharge line is a pressure reduction valve 23. This, as will appear more fully hereinafter, serves to maintain a pressure differential between the reaction chamber and the evaporator and permits the evaporation of lighter fractions of the synthetic crude.

The evaporator is provided, adjacent its bottom portion, with a drawoff line 24 through which residual liquids may be discharged. To insure a continuous operation with the minimum of manipulative time expenditure the withdrawal of liquid is made automatic. This may be accomplished by providing a control valve 25 operable, in the well known manner, by a liquid level regulating device 26. By this mechanism liquid residue in the evaporator is withdrawn and a predetermined minimum liquid level maintained.

The oil vapor fractions which pass over from the evaporator are adapted to be further treated to secure the desired fractionation and to relieve the ultimate fraction of any entrained or dissolved gases. To do this the evaporator is connected, by an overhead drawoff line 27, to a dephlegmator 28. The vapor drawoff line, as shown, leads from the upper section or dome of the evaporator to the lower portion of the dephlegmator. In the dephlegmator the vapors are percolated through a vertical series of oil pools and are relieved of their heavier constituents. The size of the dephlegmator, quantity of liquid oil, temperature of the successive pools and speed of flow of the vapors may be regulated to secure the desired ultimate vapor fraction. It will be appreciated that, if desired, the temperature of the several oil pools may be controlled by introducing an extraneous cooling medium. In the present method these conditions are so adjusted as to obtain a vapor product which has the characteristics of commercial gasoline.

The condensates formed in the dephleg-

mator gravitate to the bottom and are automatically drawn off through the line 29. This automatic operation is secured by utilizing a valve 30 controlled by the liquid level 5 regulating device 31, these two elements being similar to the valve and associated regulating device connected to the evaporator. This condensate is adapted to be recycled through the heating coils in a manner to appear more fully hereinafter.

From the dephlegmator the cleansed and fractionated vapors are drawn off through a vapor line 32 and subjected to condensation. This condensation may be achieved by connecting the line 32, as at 33, to provide a cooling coil of requisite size. The cooling coil may be enclosed within a condenser box 34 supplied with a suitable cooling medium. The cooling medium is preferably passed in 20 counter-current flow through the box. This medium, which may be water, oil, brine or any other suitable liquid, is admitted through the line 35 and withdrawn through line 36.

From the condensing stage the oil, together with incorporated gases, is passed through line 37 to the gas separator 38. This is provided at its lower portion with a liquid drawoff line 39 controlled by the valve 40. The gases, separated in this element, may be 25 withdrawn through the overhead line 41 controlled by a suitable valve 42. This gas line 41 may connect with a storage tank (not shown) or communicate directly with the burners 5. The gasoline-like constituents 30 withdrawn through the line 39 may be transferred to a storage tank or subjected to any desired subsequent treatment.

If desired, suitable valve controlled steam lines 43 and 44 may be connected to the lower 40 portions of the evaporator and dephlegmator respectively, to facilitate separation of vapors. The ends of these pipes may be perforated to secure an equal and wide distribution of the distilling medium through the 45 oil pool. By introducing steam into the evaporator a better control of the flash point and the initial boiling point of the residual products is obtained. An introduction of steam into the dephlegmator facilitates the 50 removal of the lighter ends and insures a clear-cut fractionation of the desired products.

The liquid drawoff from the dephlegmator connects with the feed line 15 by means of 55 the pipe extension 45. Interposed in the line 15, between the line 45 and the charge pump 16 is a control valve 46. Also connected in the line 15, at the other side of line 45, is a second control valve 47. By closing valve 60 47 and opening valve 46 all of the reflux condensate from the dephlegmator may be recycled to the furnace. Similarly by closing valve 46 and opening valve 47 these condensates may be directed to storage. By fixing 65 the valves at intermediate positions any pre-

determined quantity of condensate may be charged to the furnace to obtain the desired mixture of reflux with fresh feed.

When the apparatus is on stream fresh oil, forced through line 11, is preheated in the coil 14 and, after any desired percentage mixture with heated reflux, is charged to the furnace. In the heating stage the temperature and velocity of the oil is so regulated that it attains the cracking temperature and the conversion reaction is initiated. This control of conditions is exercised so that the major cracking reaction will take place in the chamber. By this means carbon deposition takes place largely in the 75 chamber, instead of in the tubes. This is advantageous for the reason that the removal of carbon from the chamber may be accomplished more expeditiously.

In the tubes the oil may be heated to temperatures ranging from 600° to 1000° F. During its course of travel through the tubes and chamber the oil is subjected to pressures which are maintained at sufficient magnitude to retain the oil largely in liquid phase. The pressure may be maintained from about 80 400 to 1000 lbs. per square inch, depending on the character of the oil treated and the temperatures to which it is subjected.

The hot oil is passed from the heating coils through a transfer line 8 to the reaction chamber 18. This, it will be understood, may be heavily insulated to conserve the heat attained in the tubes. Due to this enlarged area the chamber provides a zone in which the speed of flow of the oil is considerably reduced and assures the necessary reaction time for the oil. The major quantity of carbon which has formed during the cracking reaction is deposited in the chamber.

After the oil has traversed the length of the chamber it is passed out through the transfer line 21 to the evaporator. During this passage the pressure is relieved by means of the reduction valve 23. While any desired degree of pressure may be maintained on the evaporator, dephlegmator, condenser and receiver, it is preferable to maintain these elements at substantially atmospheric pressure. As the oil passes from the zone of high pressure, in the chamber, to a zone of lower pressure, in the evaporator, those fractions which will volatilize at the effective temperature of the synthetic crude will pass overhead. As evolved vapors and gases pass 110 upwardly through the evaporator they are subjected to the cooling action of the fresh feed and certain of the higher boiling point constituents are knocked back. The remaining uncondensed fractions pass overhead through the line 27 and are injected into the lower portion of the dephlegmator. In their upward travel through the dephlegmator the vapors are progressively relieved of heavier 115 fractions, in the manner described. The 120 125 130

lower boiling point or gasoline-like constituents which are uncondensed in the dephlegmator pass to the condenser 34 wherein the condensable components are liquefied.

5 From this element the liquid distillate, together with entrained or occluded fixed gases, are passed to the gas separator wherein the liquid and gaseous components are separated.

10 While such a process which utilizes the contained heat of the oil for distillation does present high heat economies, it nevertheless is subject to certain drawbacks. When high temperatures and pressures are employed in 15 the conversion stage and the evaporator is operated at or near atmospheric pressure a very large pressure differential obtains. As a result there may be such a vigorous and extensive distillation as to drive off a greater 20 part of the liquid products, leaving a very heavy sludge or even a solid residue. While the release of pressure by the valve 23 causes a rapid expansion of gases and vapors, the cooling effect of these is not of such a magnitude as to sufficiently modify the temperature 25 of the oil.

The present invention comprehends a method of overcoming the disadvantages by introducing into the synthetic crude a clarified 30 relatively cool hydrocarbon, substantially none of which will volatize at the temperature and pressure conditions obtained in the evaporator.

The advantages of such a step are manifold. Since the injected oil is at a lower 35 temperature than the synthetic crude it serves as a temperature modifying medium by exercising a cooling effect on the hot products of conversion. It will be appreciated 40 that by regulating the temperature and quantity of the injected oil, any desired degree of thermal control may be obtained. Since the character of the vaporized products is a function of the temperature of the 45 oil body, the introduction of cooler oil serves to govern or control the range of these volatiles.

A second and advantageous function subserved by this treatment is the maintenance 50 of a pool of liquid oil in the evaporator and a continuous flushing or purging of this element of suspended or deposited carbonaceous material. This makes for efficient operation 55 and aids materially in protracting the effective running time of the unit. Furthermore by introducing a clarified or carbon-free oil into the bottom of the evaporator, such precipitated carbonaceous material as is present 60 in the evaporator is more readily taken up and retained in suspension.

These advantages may be secured by causing 55 the residual oil in the evaporator to pass through a cooling and clarifying apparatus and then back into the oil pool in the evaporator. In this manner the oil which has al-

ready undergone distillation is employed and hence will contain only those heavier fractions which will not evaporate at the temperature conditions in the evaporator.

The apparatus for accomplishing this 70 treatment may comprise a cooling coil and an associated carbon separator. As shown, the drawoff line 24 is convoluted as at 48 and positioned within the cooling box 49. As shown in more detail in Figure 2, this cooler 75 is provided with a fluid inlet line 50 and discharge line 51 so that the device operates on the counter-current flow principle. The cooling medium may be water, brine, oil, or any other desired fluid.

80 The end of the cooling coil 48 connects with the upper portion of a carbon trap 53. This trap may comprise a closed cylindrical container having a conical bottom portion 54. Connected to the bottom of the conical portion is a valve residue drawoff line 55. Positioned within the main container is a cylindrical stand pipe 56. This is integrally fastened to the upper closure of the trap 85 and at its bottom portion is in open fluid communication with the interior of the trap. The end of the stand pipe is preferably formed with a foraminous member or screen 57 which permits the passage of liquid oil but obstructs the flow of suspended solids. 90 If desired the trap may be covered with suitable insulating material 52, as shown in Fig. 2.

95 The outlet of the cooling coil 48 communicates with the annular chamber defined 100 by the concentric members 53 and 56. The outlet pipe 58 passes through the top of the trap and descends well into the interior of the stand pipe. The other end of this 105 pipe is connected, through the charging pump 59 and feed line 60, to the transfer line 21 on the low pressure side of the valve 23. While the line 58 is shown as directly connected to the pump, it will be understood 110 that it is within the scope of the invention to interpose an accumulating or cooled oil storage tank between these two elements. By utilizing a storage tank of this character a constant source of cold tempering oil is made available for the evaporator. 115 This accumulating tank, it will be understood, may be connected to a larger oil storage tank to which oil in excess of that required for cooling purposes may be directed. If an accumulator tank is not employed the 120 excess of clarified oil may be drawn off through the line 61 to suitable storage.

125 The operation of these associated elements will have been appreciated from the foregoing description. The residual oil in the evaporator is continuously passed through the cooler 48 and carbon separator 53. In the cooler the temperature of the liquid products is reduced. The cooled oil is discharged into the annular space between the 130

cylinders 53 and 56 and therein forms a relatively quiescent pool, the speed of flow in the separator being proportionate to the cross sectional ratio obtaining between the 5 coil and the separator.

In the separator the heavy carbonaceous material settles or gravitates to the lower conical section and may be continuously withdrawn through the valve line 55. The 10 lighter or clarified oil rises in the stand pipe 56 and during this passage larger suspended solids are obstructed by the filter 57. It will be understood that in lieu of a single foraminous member 57 several such members 15 may be employed. These, if desired, may be of varying mesh so as to insure a more complete separation of solids. The clarified supernatant oil is withdrawn through the line 58 and discharged to an accumulator 20 tank or directly to the evaporator.

As shown in Figure 3 the cooling and clarification may be accomplished in one apparatus. This may be done by eliminating the cooling coil and housing the carbon 25 separator 53' directly within a cooler box 49'. This cooler, like condenser 49 is provided with cold medium inlet line 50' and outlet 51'. In operation of this device the cooling medium in the cooler abstracts heat 30 from the hot oil admitted to the separator through line 24. This oil, in its downward passage in the separator, is cooled and the heavier material settles, while the clarified lighter material rises in the stand pipe and 35 is withdrawn through the drawoff line 58'.

As has been pointed out hereinbefore the oil which is treated in the separator has previously been subjected to distillation conditions and hence has been relieved of substantially all of those fractions which will 40 vaporize at the temperature and pressure conditions in the evaporator. In this manner a hydrocarbon tempering medium is employed which not only exercises the desired 45 temperature control, but also serves effectively as a flushing agent and solvent for the residual material in the tower.

It will be understood, of course, that two or more carbon traps may be associated with 50 the tower and bypassed to the tower so that they may be cut in and out to permit cleaning of one while the other is in operation.

The present process permits a very accurate control of the overhead products, for by 55 modifying the temperature of the synthetic crude in the evaporating stage practically any desired fractionation can be obtained at the initial point of distillation. In addition to this, the character of the evaporator bottoms is so controlled or governed that from 60 such residues a marketable fuel oil may be readily secured.

While a particular apparatus has been described as being especially suited for the process, it is to be understood that any mechanical

modification which will subserve equivalent functions may be employed.

I claim:

1. A process of converting hydrocarbon oil comprising subjecting the oil to cracking conditions of temperature and pressure in separate heating and digesting stages, passing the products of conversion to an evaporating stage maintained at a pressure materially lower than that in the digesting stage, distilling off the lighter fractions of the products of conversion, withdrawing unvaporized products from the evaporating stage, cooling and removing solid carbonaceous material from the unvaporized products and cooling the products of conversion before passing them to the evaporating stage by mixing the cooled carbon free unvaporized products with the products of conversion from the digestion stage before introducing the same into the evaporating stage. 70

2. An evaporating apparatus for treating petroleum products comprising a tower, a liquid inlet to the tower, a pressure reduction valve in the inlet line, a discharge line 90 for the tower, a cooling device and carbon separating chamber interposed in the discharge line and a fluid conduit directly connected to said chamber and the low pressure side of the inlet line. 95

3. A process of treating hydrocarbon oils comprising subjecting the oil to conversion conditions of temperature and pressure in a heating zone, passing the oil from the heating zone to an enlarged reaction zone wherein the conversion instituted in the heating zone may be consummated, passing the products of conversion to a vaporizing zone maintained at a reduced pressure wherein light fractions of the products of conversion will be vaporized, withdrawing and treating the vapors to obtain desired fractions, withdrawing the unvaporized residue from the vaporizing zone, cooling it, separating carbonaceous suspended matter mixing the clarified residue with the products of conversion passing to the vaporizing zone prior to introducing the products of conversion into the vaporizing zone to temper the products of conversion and prevent excessive vaporization. 100 105 110 115

4. An apparatus for converting hydrocarbon oil comprising a furnace having a coil therein, an enlarged digestion chamber connected with said coil, and means for forcing a hydrocarbon oil through said coil into the digestion chamber, an evaporator, a conduit connecting the discharge end of said digestion chamber with the evaporator, and means in said conduit for reducing the pressure on material passing from the digestion chamber to the evaporator, a carbon separating chamber, a discharge line from the lower portion of said evaporator connected with the inlet to said carbon separating chamber, 120 125 130

means interposed in said line for cooling material passing from the evaporator to the carbon separating chamber, and means for withdrawing clarified oil from said carbon separating chamber and introducing the same into the conduit connecting the digestion chamber with the evaporator.
